(**) Term: **14 Years**

The ornamental design for a thread cassette for an embroidery machine, as shown and described.

(21) Appl. No.: **29/175,177**

DESCRIPTION

(22) Filed: **Jan. 31, 2003**

FIG. 1 is a front view of a first embodiment of a thread cassette for an embroidery machine;

Related U.S. Application Data

FIG. 2 is a rear view thereof;

(62) Division of application No. 29/168,762, filed on Oct. 9, 2002, which is a division of application No. 29/151,302, filed on Dec. 7, 2001, now Pat. No. Des. 467,595.

FIG. 3 is a left view thereof;

(30) **Foreign Application Priority Data**

FIG. 4 is a right view thereof;

Jun. 13, 2001 (JP) 2001-17202

FIG. 5 is a top view thereof;

(51) LOC (7) Cl. **15-06**

FIG. 6 is a bottom view thereof;

(52) U.S. Cl. **D15/72**

FIG. 7 is a perspective view thereof;

(58) **Field of Search** D15/66-72; D14/420;
112/445-448, 236, 121.11, 121.12, 217.1,
258-262

FIG. 8 is a front view of a second embodiment of a thread cassette for an embroidery machine;

(56) **References Cited**

FIG. 9 is a rear view thereof;

U.S. PATENT DOCUMENTS

FIG. 10 is a left view thereof;

D369,171 S 4/1996 Honson

FIG. 11 is a right view thereof;

FIG. 12 is a top view thereof;

FIG. 13 is a bottom view thereof; and,

FIG. 14 is a perspective view thereof.

The broken line showing is for illustrative purposes only and forms no part of the claimed design.
